MOP

Harvey M. Merchant, Minneapolis, Minn.

Application July 10, 1933, Serial No. 679,731

7 Claims. (Cl. 15—147)

My present invention relates to mops of the type which comprise flexible swab holders and flexible swabs or mop heads applied thereto and, generally stated, the invention consists of the novel construction, combinations and arrangement of parts hereinafter described and defined in the claims.

The term "mop" is herein used in a broad sense to include dry mops or dusters, as well as wet mops.

The objects of the invention, generally stated, are production of a mop at comparatively low cost which will be light in weight, will have the desired resilience both in the plane of the holder and perpendicular to said plane, and certain other advantages, as will hereinafter appear in connection with the description of preferred construction and arrangement thereof.

In the drawings, which illustrate the invention, wherein like characters indicate like parts throughout the several views—

Fig. 1 is a perspective showing the improved mop including the swab holder and a handle for the latter;

Fig. 2 is a perspective showing the mop with the swab removed from the swab holder;

Fig. 3 is a view in elevation showing the swab removed from the holder and laid out flatwise, the main intermediate portion thereof being broken away or removed;

Fig. 4 is a detail in section taken in the plane of the line marked 4—4 on Fig. 2;

Fig. 5 is a detail in section taken in the plane indicated by the line 5—5 marked on Fig. 2;

Fig. 6 is a view corresponding to Fig. 4, but illustrating a slight modification;

Fig. 7 is a perspective illustrating somewhat modified form of mop wherein the swab, instead of being annular in form, is in the form of a mit-like complete casing fitting around the holder;

Fig. 8 is a view corresponding to Fig. 2, but illustrating a modified form of swab holder used for the mit-like swab shown in Fig. 7;

Fig. 9 is a transverse section taken on the line 9—9 of Fig. 7; and

Fig. 10 is a plan view showing, on a small scale, the zig-zag spring bent flatwise in a common plane into the form of a rectangular loop.

Figs. 7, 8 and 9 illustrate a third and Fig. 10 a fourth form of the improved model.

Referring to the structure illustrated in Figs. 1 to 5, inclusive, the numeral 10 indicates a handle in the form of a pole shown as provided at one end with a rigidly secured projecting screw-threaded stud 11. The stud 11 in this particular

instance, is adapted to be passed freely through the rear wall and screwed into an internally threaded boss 12 of a clamping head in the form of a flattened metal tube 13. The swab holder, as illustrated, is in the form of a flat spring 12 that is primarily bent zig-zag in a common plane, by means of alternately bent U-shaped folds. To give the same kind of resilience and elasticity to the said spring, from end to end, the U-shaped folds thereof should be made constant or alike from end to end of the spring. The spring 14 is then bent into the form of a loop and its opposite ends are inserted into the opposite ends of the flat clamping head 13 and there secured by suitable means.

As a simple means for securing the inserted ends of the spring within said clamping head, the stud or trunnion 11, see particularly Fig. 4, is passed through one of the loops of one inserted end of said spring; and the head 13 at the other end is bent inward at 15 to permanently hold that end of the spring within the head. In the particular arrangement described, one end of the spring may be released from the head whenever the head is unscrewed from the handle.

For application to the spring bent into the form shown, there is provided a swab or mop head 16, the tufts of which are shown as secured to a tape or flexible hem in the form of a flattened tube 17 through which the spring is adapted to be readily inserted when one end thereof is released from the clamping head 13. The ends of the hem 17 are telescoped onto the ends of the clamping head 13.

As a swab holder, the flat zig-zag spring described has many highly desirable features. To give the desired flexibility to the spring, the length of the U-shaped folds transversely of the spring should be considerably greater than the width of said folds measured in a direction longitudinally of the spring. Such a spring, when bent into a loop, has its greatest flexibility in the plane of the loop. This arrangement, it has been found, is highly desirable in mops generally. For example, when the mop illustrated completely in Fig. 1, is thrust against a flat wall or surface, it will readily flatten out and the swab will be brought against the entire flat surface within its range, but will, of course, instantly spring back to normal substantially round form when relieved from pressure.

Moreover, this spring, arranged as described, has its greatest resistance to deformation perpendicular to the plane of the loop, so that a mop will be forced with sufficient pressure against the

floor or any object in which it is brought into contact.

It is very desirable that the ends of the flat zig-zag spring be inserted in or secured to the clamping head of the handle in such a way that the complete spring is primarily held in approximately circular or cylindrical form. Such manner of application has two important advantages, to wit:

- 10 10 (a) When the mop handle is turned say to a position perpendicular to the plane of the loop of the spring, the resistance to such turning action will be transmitted through the body of the spring, and the spring will not be bent short at any one point. Thus breaking of the spring or bending the same beyond its limit of elasticity is avoided.
(b) The spring holder as thus arranged and applied, is capable of being turned with the mop 20 or otherwise completely over against the handle 10. This turning of the spring has the effect of turning the same inside out, in a sense, so that the spring, when turned beyond a certain point close to the handle, will tend to spring against the handle and will remain pressed against the handle this will shorten up the mop, and this is desirable for the purpose of storage and shipment. The action just above described will be produced if, for example, the handle 10 be held in one hand 30 and the mop swab and spring be bent upward or downward until the swab bears against the hand-piece; and it will be found that when the swab has been pressed against the hand-piece as stated, the spring will have been turned to such 35 a position that it will then exert its pressure to hold the swab against the hand-piece.

In Fig. 6, the construction is the same as that hitherto illustrated, except that in lieu of the stud or trunnion 11, a wood screw 11^a is passed through the clamping head 13^a and screwed into the end of the holder or pole 10^a.

Figs. 7, 8 and 9 show a modification of the mop holder and swab in which two flat zig-zag springs 14^a and 14^b are employed in eccentric arrangement. The ends of the springs 14^a and 14^b are brought together and together inserted into the clamping head 13^a substantially the same as when the single spring 14 is employed. For application around the springs 14^a and 14^b there will be employed a mop swab or head in the form of a mit or complete casing 19. This mop casing need have a comparatively small opening extending say from points a to point b on Fig. 7, for the springs 14^a and 14^b are capable of being pressed laterally so that they will go through a comparatively narrow opening.

In Fig. 10, the spring and swab holder are bent zig-zag in a common plane, and are in the form of a rectangular loop, as indicated by the character 14^d, and its ends are indicated as suitably secured to a handle 10^d by means of a head 15^d.

5

What I claim is:

1. A mop comprising a handle, a swab holder in the form of a flat zig-zag spring bent throughout its length to form alternate substantially U-shaped folds, said spring being bent into the form 10 of a loop and having its ends secured to said handle, and a swab applied to said holder and partaking of the resilience thereof.
2. A mop comprising a handle, a swab holder in the form of a flat zig-zag spring bent to form 15 a loop and having its ends secured to said handle, the flat dimension of said spring being in the direction of the axis of the loop, and a swab applied to said holder and partaking of the resilience thereof.
- 20 3. The structure defined in claim 1 in which the length of the U-shaped folds transversely of the said spring is considerably greater than the width of said folds measured in a direction longitudinally of the spring, said spring having its 25 greatest flexibility and least resistance to deformation in the plane of the loop.
4. The structure defined in claim 2 in which said flat zig-zag spring has approximately U-shaped folds that are of greater length transversely of the spring than width longitudinally of said spring, said spring having its greatest 30 flexibility and least resistance to deformation in the plane of the loop thereof.
5. The structure defined in claim 1 in which 35 said swab holder comprises also a second spring of the character first defined having its ends secured to said handle and its body portion in eccentric arrangement in respect to the first noted spring.
- 40 6. The structure defined in claim 2 in which said swab holder comprises also a second spring of the character first defined having its ends secured to said handle and its body portion in eccentric arrangement in respect to the first noted 45 spring.
7. The structure defined in claim 2 in which said handle has a clamping head gripping the ends of said spring and holding said ends diverging therefrom in approximately opposite directions whereby deflection of said spring transversely from the normal plane of its loop will deform the folds of said spring.
